POLICE HELMET

John N. McMurry, Hawthorne, Calif.

Application September 13, 1956, Serial No. 42,916

Term of patent 14 years

(Cl. D3—13)

Fig. 1 is a side elevational view of a police helmet showing my new design;

Fig. 2 is a front elevational view; and

Fig. 3 is a rear elevational view thereof.

The essential features of the design reside in the portions shown in solid lines on the drawing.

I claim:

The ornamental design for a police helmet, as shown and described.
